UNITED STATES PATENT OFFICE.

HENRY E. HUBBARD, OF CHICAGO, ILLINOIS, ASSIGNOR TO ADDRESSOGRAPH COMPANY, OF CHICAGO, ILLINOIS, A CORPORATION OF ILLINOIS.

RIBBON SPOOL.

Application filed August 17, 1925. Serial No. 50,594.

This invention relates to ink ribbon spools of the kind referred to in companion applications Serial No. 52,503 and Serial No. 52,505, filed August 26, 1925.

5 The object of this invention is to provide simple means for securing the edges of the spool together upon the end of the ribbon in a manner which will prevent substitution of a new ribbon when the original ribbon 10 becomes worn.

The invention is adaptable for use with a spool of the kind set forth in my companion applications mentioned, which is of a special construction, to cooperate with parts 15 of a ribbon mechanism for certain purposes, and one of the objects of this invention is to construct the spool and to fasten the ribbon thereto in such a way that when the ribbon is worn out the spool and ribbon 20 must be thrown away and entirely replaced, instead of simply replacing the ribbon on the spool.

Referring to the drawings,

Fig. 1 is a view of the spool blank before 25 it is bent into spool shape and showing one embodiment of the invention.

Fig. 2 is a similar view showing another embodiment of the invention.

Figs. 3 and 4 are sectional views showing 30 spools made from the blanks of Figs. 1 and 2 respectively.

Figs. 5 and 6 are detail views of another modification of the invention.

Referring to the drawings, the spool is 35 made preferably of light gauge metal from a blank 7 which has the parallel openings 8 stamped therein in accordance with the invention of my companion applications and is also provided at its edges with inter- 40 engaging prongs and openings to secure the edges together upon an interposed ribbon 9. In Fig. 1 triangular shaped prongs 10 are stamped from the blank adjacent one edge to project inward of the spool, and oblong 45 openings 11 are stamped in the margin 12 at the other edge of the blank to receive said prongs. The margin 12 is depressed or offset to lie in a plane below that of the remainder of the blank so that when the blank 50 is shaped in the form of a spool, as shown in Fig. 3, the margin will be depressed to receive the pronged edge of the blank, and the end of the ribbon, so that the outer surface of the spool will be uniformly concentric with the center. In Fig. 1 the prongs

are stamped from the blank lengthwise thereof and the openings 11 are oblong in shape and extend lengthwise of the blank to receive the prongs, the openings being of just sufficient size to accommodate the 60 prongs. In Fig. 2 the prongs 13 are stamped from the blank transversely thereof and the oblong openings 14 extend transversely of the blank to receive these prongs. In Figs. 5 and 6 the prongs 15 are of right angle shape and extend lengthwise of the blank, which will be provided with openings like 11, Fig. 1, to receive these prongs.

In assembling a spool made from the blank of Fig. 1, the blank is formed in spool shape, the end of the ribbon is laid upon the depressed margin 12, and the prongs are forced through the ribbon and projected through the openings 11, after which the prongs are bent upward against the underside of the depressed margin 12 to clinch the prongs and to secure the edges of the spool together upon the interposed ribbon. These prongs are bent beneath the opening 70 formed when the prong is stamped out to block the opening on the underside of the spool so that it will be impossible to insert a pin or wire or other device through the opening formed by stamping the prong and the registering opening 11 to secure a replacement ribbon upon the spool.

The spool of Fig. 4 is formed from the blank of Fig. 2 in the same manner as hereinbefore described in connection with the spool of Fig. 3; and a spool will be formed 90 from such a blank as is shown in Figs. 5 and 6 in the same manner. The long side of the right angle shaped prong 15 is presented to the ribbon as the latter is inserted between the overlapping portions of the 95 spool and this prong presents less obstruction to the insertion of the ribbon than the prong 13 of Fig. 2, and possibly of the prong 10 of Fig. 1. The spool is provided with an inwardly directed flange 16 to engage a driver of the ribbon mechanism for turning the spool, and also with a lug 17 at one end, which prevents the spool from being arranged on the driver wrong end to, as more particularly set forth in my com- 100 panion applications.

I claim:

1. An ink ribbon spool formed of sheet metal and having a plurality of triangular shaped prongs stamped therefrom along 110

- one margin and corresponding openings stamped therefrom along the opposite margin, a ribbon interposed between said margins, and the prongs being forced through the ribbon and inserted in said openings and clinched on the inside of the spool.
2. An ink ribbon spool formed of sheet metal and having a plurality of triangular shaped prongs stamped therefrom along one margin and corresponding openings stamped therein along the opposite margin, each prong projecting and each opening extending in a direction transverse of the spool, and a ribbon interposed between said margins, the prongs being forced through the ribbon and inserted in said openings and clinched on the inside of the spool.
3. An ink ribbon spool formed of sheet metal and having a plurality of triangular shaped prongs stamped therefrom along one margin and corresponding openings stamped therein along the opposite margin, and a ribbon interposed between said margins, the prongs being forced through the ribbon and inserted in said openings and clinched on the inside of the spool in a direction beneath the openings formed by stamping the prongs.
4. An ink ribbon spool formed of sheet metal and having a plurality of right angle triangular shaped prongs stamped therefrom along one margin and corresponding openings stamped therein along the opposite margin, and a ribbon interposed between said margins, the prongs being forced through the ribbon and inserted in said openings and clinched on the inside of the spool.

HENRY E. HUBBARD.
